UNITED STATES PATENT OFFICE.

PERRY A. McCASKEY, OF LAKEWOOD, OHIO.

ACCOUNT-FILING DEVICE.

1,164,830.

Specification of Letters Patent. Patented Dec. 21, 1915.

Application filed September 8, 1913. Serial No. 788,617.

To all whom it may concern:

Be it known that I, PERRY A. McCASKEY, a citizen of the United States, residing at Lakewood, in the county of Cuyahoga and State of Ohio, have invented a certain new and useful Improvement in Account-Filing Devices, of which the following is a full, clear, and exact description, reference being had to the accompanying drawings.

10 This invention relates to improvements in that class of devices commonly known as account registers, which comprise, generally, a cabinet or casing which contains a series of hinged leaves to the opposite faces of which 15 may be held, by suitable clips, account slips; the series of leaves being supported within the cabinet or casing in a manner that will permit them to be swung from a substantially vertical position to a substantially 20 horizontal position for the purpose of inspecting the slips carried upon their opposite sides.

As protection against fire and theft, the tradesmen who use registers of the above 25 type desire to place the series or pack of leaves within a safe during all but business hours, and for this reason it is highly desirable to so construct the register as to permit of the easy removal of the series or pack of 30 leaves from the cabinet or casing, and to hinge or connect the leaves of the series in a manner that will allow them to be placed closely together and in the smallest possible space. The general idea of the removal of 35 the leaves from the casing is not new, but the particular manner of connecting the leaves in my improved construction of register, whereby the leaves occupy the minimum amount of space when removed from 40 the casing, is novel.

The objects of my invention are to provide an account register of the above type from which the leaves may be quickly and conveniently removed; and to connect the 45 leaves by an extensible hinge, which will permit of a limited separation thereof; and further, to provide a leaf which is very strong, yet simple of construction and economical of production. And a still 50 further object of my invention is to construct the aforesaid extensible hinge in a manner that will allow leaves to be added to the original series or pack as occasion demands.

55 Generally speaking, my invention may be defined as consisting of the combinations of

elements set forth in the annexed claims and illustrated in the accompanying drawings forming part hereof, wherein—

Figure 1 is a front elevation and Fig. 2 a 60 sectional side elevation of an account register embodying my invention, the latter figure being taken on line 2—2 of Fig. 1; Fig. 3 is a side elevation of the series or pack of leaves removed from the cabinet or casing; 65 Fig. 4 is a perspective of a corner of the register showing the extensible hinge and fragments of the various leaves connected thereby; Fig. 5 is a perspective of one of the extensible hinge elements or links; Fig. 70 6 is a central vertical section through the extensible hinge and the supporting means therefor; Fig. 7 is a similar view of the extensible hinge in the position it assumes when the leaves are removed from the casing 75 and are close together, as shown in Fig. 3; and Figs. 8 and 9 are sectional details of one of the leaves such sections being taken on the correspondingly numbered lines of Fig. 1. 80

In the drawings, 1 represents the base of the cabinet or casing, above which is supported the table 2 by a back wall 3 and side walls 4, and a drawer 5 is adapted to slide within the space confined by these parts. 85 Rising from the rear edge of a table 2 is a wall 6, and extending forwardly from the vertical edges of this wall are a pair of side pieces 7. Two triangular blocks 8 are confined within the corner between the table 2 90 and the vertical wall 6, and each is spaced a slight distance from one of the side pieces 7. A shallow channel member 9 is secured to the inclined face of each of the blocks 8 by screws 10, and a flat headed screw 11 95 passes through the web of the channel member near its upper end and into the block, and has its head 12 spaced from the surface of the web for a purpose which will be explained hereinafter. 100

Each leaf comprises a sheet metal plate 13 which has its upper edge turned over in order to strengthen it, as shown at 14 (particularly in Fig. 9) and its lower edge is bent around a wire 15. A strip 16, preferably of wood, which is rounded at its lower end and beveled off toward its center at its upper end, is secured to each end of the plate 13 by scoring the inner side of the strip at its center and setting the edge of the plate 110 into the channel thus formed, where it may be conveniently held by brads 17. The rod

15 extends throughout the entire lower edge of the leaf and is exposed at the two places indicated at 15^a where the lower edge of the leaf is notched at 18, said notches being 5 spaced apart the same distance as the aforesaid blocks 8 which form a part of the casing. The opposite surfaces of the plate 13 are divided into sections by strips 13^a and within each section is located two spring 10 clips 13^b for securing to said leaf the account slips. The leaves are hinged together at the points where they are notched by an extensible hinge which will now be described.

The extensible hinge comprises a plurality 15 of channel shaped links 19 and 20, the links 20 being enough narrower than the links 19 to permit the links 20 to nest or telescope within the links 19. Each side wall of each 20 of the links is provided with two longitudinally disposed slots 21, each slot being located near an end of the side wall and, as will be seen clearly from Figs. 6 and 7, when the links 20 are placed within the links 19, the slots in the two links are on the same 25 level and the upper edges of the side walls of the links are in a common plane. The portions 15^a of the rods 15, where they are exposed through the notches 18 of the leaves, pass through the slots in the opposed walls 30 of the various links, the rod of the first leaf passing through diametrically opposite slots in the side walls of the first link 19, the rod of the next adjacent leaf passing through the other slots of the same link and through a 35 pair of diametrically opposite slots in a link 20 nesting therein. Telescoping over the opposite end of this last mentioned link is another of the links 19, and the rod of the next leaf of the series passes through the 40 registering slots in the side walls of these two links. This manner of connecting the leaves is carried on throughout the entire series (which may include any number of leaves) and the last link of the extensible hinge, 45 which should be of the kind indicated at 19, has its web provided with a key hole slot 19^a. The slot 19^a permits the hinge to be buttoned over the head 12 of the screw 11 whereby the hinge is effectively supported 50 within the channel member 9.

When the pack of leaves is thus supported 55 within the cabinet or casing with each of the extensible hinges occupying one of the channels 9, the series or pack of leaves is effectively held against any lateral movement; and, as will be seen from Fig. 2, the leaves are permitted to swing a little to the rear of a vertical position where they are supported by the vertical wall 6 and thus, 60 by gravity, retain their normal position. To remove the series or pack of leaves from the casing, it is only necessary to shift the pack backwardly and upwardly until the shank of the screw 11 is withdrawn from the reduced end of the slot 19^a when the enlarged

portion thereof may be drawn over the head 12 of said screw. When the leaves are removed from the register their lower edges may be placed upon a horizontal surface when they will assume a corresponding position, or one which brings the plane of their lower edges at substantially right angles to the planes of the leaves; and thereafter the individual leaves may be pressed closely together as shown in Figs. 3 and 7. This reduces the cubic capacity of the leaves to a minimum, which is a very important feature when it is taken into consideration that they have to be stored in a safe.

By the employment of my improved hinge, 80 the user of the account register may, as his needs require, add to the original series or pack of leaves such leaves as may be necessary, a casing or cabinet of sufficient size being supplied with the original pack of 85 leaves as will permit of such addition. While I have shown no fly-leaf or cover for my account register, it may be added, if found desirable; or I may omit the dividing strips 13^a and the clips 13^b from the front 90 surface of the first leaf of the pack, thus converting it into a cover for the series.

Having thus described my invention, what I claim is:—

1. A device of the character set forth comprising, in combination, a casing, a series of 95 leaves, an extensible hinge connecting the lower edges of said leaves, and an upwardly opening inclined channel member secured within the casing and adapted to contain 100 and support said hinge, the width of the hinge being substantially the same as the inside width of the channel member.

2. A device of the character set forth comprising, in combination, a casing, a series of 105 leaves, an extensible hinge connecting the lower edges of said leaves, said hinge comprising a plurality of telescoping channel members to which the leaves are connected, and an upwardly opening inclined channel 110 member secured within the casing adapted to contain and support said hinge, the width of the outer channel members of the hinge being substantially equal to the inside width of the channeled supporting member.

3. In a device of the character set forth, the combination of a series of account leaves and an extensible hinge comprising two series of channel members, the members of one series being of such width as to telescope within the members of the other series and fit closely therewithin and the members of one series alternating with those of the other series, and a pivotal connection between each channel member and a 115 leaf, there being a lost-motion connection between adjacent channel members.

4. In a device of the character described, the combination of a series of account leaves, an extensible hinge comprising telescoping 120

channel members, each side wall of each of said members being provided with a pair of longitudinally extending slots, the slots in one wall being opposed to those in the other 5 wall and the slots in adjacent ends of adjoining channel members being adapted to register, and rods carried by the leaves adapted to extend through the registering slots in the overlapping side walls of the hinge 10 members.

5. A device of the character set forth comprising, in combination, a series of leaves, each leaf having one of its edges notched and turned around a wire certain portions 15 of which are exposed through the notches in the edge of the leaf, a plurality of telescoping channel members having slots in their side walls, each member connecting the exposed portions of the wires of adjacent 20 leaves, and means for supporting the channel members and for retaining them against lateral movement.

6. A device of the character set forth comprising, in combination, a series of leaves, each leaf having one of its edges notched and turned around a wire certain portions of 25

which are exposed through the notches in the edge of the leaf, a plurality of telescoping channel members pivotally connected to the exposed portions of said wires, and 30 means for supporting the channel members and for retaining them against lateral movement.

7. A device of the character set forth comprising, in combination, a series of leaves, 35 each leaf having one of its edges notched and turned around a wire certain portions of which are exposed through the notches in the edge of the leaf, a plurality of telescoping channel members having slots in their 40 side walls, each member being connected to the exposed portions of the wires of adjacent leaves, and an upwardly opening channel member which is adapted to receive the former channel members and retain them 45 against lateral movement.

In testimony whereof, I hereunto affix my signature in the presence of two witnesses.

PERRY A. McCASKEY.
